(57) **CLAIM**

The ornamental design for a pannier for motorcycles, as shown and described.

DESCRIPTION

FIG. 1 is a front elevational view of a pannier for motorcycles showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front left perspective view thereof;

FIG. 8 is a rear left perspective view thereof;

FIG. 9 is a front right perspective view thereof; and,

FIG. 10 is a rear right perspective view thereof.

The portions of the article shown in broken lines in the Figures form no part of the claimed design.

The subject pannier is installed on a rear side portion of a motorcycle as a container.
